UNITED STATES PATENT OFFICE

LUTHER R. HANNA, OF INDIANAPOLIS, INDIANA

AUTOGRAPHIC MANIFOLDING MACHINE

Application filed September 12, 1932. Serial No. 632,661.

This invention relates to autographic manifolding devices and has for one of its primary objects the provision of means for shifting sets of copies from a position to be written upon to positions permitting the copies to be removed without having to employ feed rollers or the like heretofore customarily used.

A further important object of the invention is to provide stationary pin members over which a set of copies may be engaged during the writing operation whereby the copies are maintained in a rigid non-shifting position while they are being written upon.

A still further important object of the invention is to provide means for retaining one of a number of copies in each set in such a manner that the retained copies may be held from view under lock and will be placed in a folded condition.

Other objects and advantages such as the forming of a very simple mechanism capable of being produced at a relatively low cost, ease and simplicity of operation, and reliability under severe operating conditions, will become apparent to those versed in the art in the following description of the invention which is shown in one particular form in the accompanying drawings, in which

Fig. 1 is a fragmentary top plan view of a structure embodying my invention;

Fig. 2, a longitudinal vertical section through the structure on the line 2—2 in Fig. 1;

Fig. 3, a vertical transverse section through the structure on the line 3—3 in Fig. 2;

Fig. 4, a detail in vertical longitudinal section on a slightly enlarged scale showing a safety pin at the end of its rearward travel;

Fig. 5, a vertical longitudinal section similar to Fig. 4 but showing the pin at the end of its extreme forward travel;

Fig. 6, a fragmentary side elevation of the structure;

Fig. 7, a fragmentary rear end elevation, and

Fig. 8, a detail in rear end elevation on a slightly enlarged scale showing the carbon paper position in the device.

Like characters of reference indicate like

parts throughout the several views in the drawings.

I form a box-like housing 10 entirely open at the front and back ends and also open across its top. In other words the housing 10 is formed to have a floor 11 and the two side walls 12 and 13. Spaced upwardly from the floor 11 guides 14 and 15 are fixed respectively to the side walls 12 and 13 to extend horizontally therealong from the rear ends of the walls to at least past the center of the walls. Slides 16 and 17 are slidably retained within the guides 14 and 15 respectively so as to be shiftable longitudinally therealong. The slides 16 and 17 each has a length substantially equal to that of the sides 12 and 13 whereby the slides will normally extend forwardly from the guides.

A carriage 18 here shown as being substantially a rectangular box-like structure is carried by the slides 16 and 17 by means of posts 19, 20 extending laterally from the sides of the carriage to engage the slides. This carriage 18 is open from both the front and rear ends and carries a top platform 21 spaced downwardly a distance from the top edges of the sides 12 and 13 of the housing 10. The width of the carriage 18 is less than the distance between the side walls 12 and 13, the carriage being here shown, Fig. 7, as being located to have its longitudinal center line somewhat to the left of the corresponding center line of the housing 10.

A carbon paper housing is formed along the right side of the carriage 18 by extending a floor 22 horizontally from the side and then carrying a wall 23 vertically upward so as to provide space between this wall and the side of the carriage within which brackets 24, 25 may be located so as to carry a spool 26 revolvably therebetween to have the spool axis horizontally disposed. The top end of the wall 23 terminates just below the level of the top edge of the housing side 13 and has hinged thereto a carriage cover 27. At the rear end of the carriage 18 are a pair of fingers 28 and 29 fixed to the respective sides of the carriage and turned inwardly toward each other to be spaced upwardly a slight distance from the platform 21. The cover 27

normally rests on these inturned fingers to be spaced thereby above the platform 21. The cover 27 has a window 30 cut in it to have a shape corresponding to that of a form 5 to be used in the device, this window being centered laterally over the platform 21. At the forward end of the cover 27, a handle 31 is mounted transversely thereacross as a means for shifting the carriage longitudinal 10 ly of the housing 10. At the left front corner of the cover 27 is a spring latch 32 fixed to the downturned apron about the cover 27 to extend forwardly to have a pin 33, see Fig. 1, normally entered through a hole in the side 15 of the carriage 18 whereby the cover 27 is releasably held in the closed position, the latch 32 being formed of spring material so that it may be pushed outwardly to withdraw the pin 33 from engagement through 20 the carriage wall. The carriage has a length sufficiently great to receive therein a drawer 34 from the rear end. This drawer 34 is formed to have a rear end sufficiently large to cover over the back opening into the carriage 18 and extends upwardly to be engaged under the downturned apron 35 across the back end of the cover 27. The drawer may be withdrawn from the carriage by raising the cover 27 as indicated by the dash lines 25 in Fig. 7.

The housing 10 is provided with a transverse partition 36 located sufficiently forward within the housing as to permit the carriage 18 to be fully received within the 30 housing. A latch 37 is fixed to the partition 36 to extend rearwardly so as to engage over the inwardly and rearwardly turned ear 38 on the carriage 18, Fig. 1, when the carriage is moved forwardly to its forward limit of 35 travel. By reason of this latch 37, the carriage 18 can not fall out of the housing 10 should the front end of the housing be lifted. In order to release the carriage so as to permit backward movement thereof, I provide a 40 lever 39 rockably attached to the side 12 of the housing and carry this lever upwardly to have it extend a slight distance above the top of the side. On this lever I fix an inturned leg 40 which is directed toward the side of the 45 latch 37 and has its end in the path of a cam 41 on the latch so that by pushing the lever 39 forwardly the leg 40 will bear against the cam 41 and thus press the latch 37 inwardly and out of engagement with the ear 38. The 50 latch 37 being made out of spring material will tend to return the lever 39 to its normal rear position by reason of the inclination of the cam 41 tending to urge the leg 40 rearwardly under the pressure of the latch. 55 A rack 42 is fixed along the side 12 above the guide 14 to be immediately under a pair of dogs 43, 44 which are rockably mounted on a block 45 fixed to the side of the carriage 18. These dogs 43 and 44 normally drop 60 under the influence of gravity to have their

outer ends engage between the teeth of the rack 42 which would ordinarily prevent movement of the carriage in either direction. In order to obtain selective movement of the carriage, the block 45 is fitted with a 70 longitudinally slid able bar 46, Fig. 6, which has an outturned pin 47 extending through the block to between the dogs 43 and 44. By selectively shifting the bar 46 forwardly and rearwardly, the respective dogs may be lifted 75 from engagement with the rack so as to permit movement of the carriage in either direction depending upon which dog is lifted. A stop 48 is fixed on the lever 39 to be in the path of the bar 46 so that when the 80 carriage 18 is shifted to its forward limit of travel, the bar 46 has been pushed rearwardly upon striking this stop so as to lift the dog 44 and allow the dog 43 to drop against the rack. In this position of the bar 85 46, the carriage 18 upon being released from the latch 37, may be carried rearwardly since the dog 43 having a forwardly directed rack contacting end will merely drag over the rack and the rear dog 44 is held clear of the rack. 90 At the desired rear limit of travel of the carriage 18, a stop 48 is fixed to the inner side of the wall 12 to be in the path of the bar 46 so that when the bar 46 is pressed against the stop it is shifted forwardly to drop the 95 dog 44 against the rack 42 and the other dog 43 is lifted clear of the rack. This arrangement of the dogs 43 and 44 and the rack 42 is provided so that once the carriage 18 is started from either the forward or rear limits 100 of travel, the carriage must be carried on to the opposite limit and can not be reversed in its direction of travel between those two limits. An adjustable stop 49 is fixed to the floor 11 of the housing 10 to be in the path 105 of an arm 50 extending from the carriage 18 so as to positively limit the rearward travel of the carriage, the adjustment being provided to obtain the exact location of this limit.

A plate 51 has its forward end fixed to the partition 36 to extend horizontally rearwardly therefrom to within the carriage 18 and compressively against the under side of the platform 21. The platform 21 is provided with two laterally spaced apart holes toward 115 its rear end through which springs 52, 53 extend to bear normally against the under side of the cover 27. Longitudinal slots 54, 55 are cut in from the rear end of the plate 51 to permit the springs 52, 53 to enter therewithout hindrance so that the carriage 18 may be shifted forwardly without interference thereby. Toward the forward end of the plate 51, I mount two transversely spaced apart pins 56 and 57 to rigidly extend 120 above the plate 51 for a slight distance and fix guides 58 and 59 to rise above the plate 51 and extend over the tops of the pins to terminate with forwardly extending ends 125 to form hooks in front of and above the pins. 130

One pin or more than two may be used. Under the handle 31 and above the cover 27 is rockably mounted a plate 60 to have forwardly turned arms 61 and 62 which are 5 spaced apart to center with the pins 56 and 57 respectively. Against the under sides of these arms are mounted respectively safety pins 63 normally tending to pull the plate 60 downwardly by its forward side under the 10 influence of gravity and being further urged downwardly by means of a light spring 64 under the rear side of the plate. The forward end of the platform 21 is notched out to permit these pins 63 to drop against the 15 plate 51. The pins 63 are each notched across its under side to provide a slot sufficiently wide such that when the carriage 18 is moved forwardly, the pins 63 may ride over the guides 58 and 59, the guides entering the slots 20 in the under sides of the pins. A pair of fingers 65, 66 are fixed against the under side of the cover 27 to extend forwardly one on each side of the respective pins 63, the forward ends of these fingers terminating some- 25 what back of the front sides of the pins 63.

A plate 67 is fixed across the top edges of the sides 12 and 13 forwardly of the pins 56, 57 and carries a rear turned apron 68 which slopes downwardly toward the plate 30 51 to terminate by its rear lower edge at about the level of the top ends of the pins 56, 57. A tongue 69 extends on down and rearwardly centrally between the pins 56, 57 to terminate centrally between the pins and with sufficient 35 clearance between it and the plate 51 to permit the passage of a sheet of paper therebetween, the rear point of the tongue being at a lower elevation than the top ends of the pins 56, 57. A housing cover 70 is provided with 40 downturned edges to fit over the sides 12 and 13 and is rockably attached to the sides by the screws 71 and 72 under the plate 67 so that the cover may be lifted from the rear end as indicated by the dash lines in Fig. 6. 45 This cover 70 is provided with an elongated window in its top side through which the handle 31 extends. The window in this cover 70 is of sufficient length to permit the carriage 18 to travel the full distance between 50 the front and rear limits. The front end of the window is notched out to give clearance for the vertical travel of the pins 63 and their supporting arms. The forward portion of the housing 10 in front of the plate 67 is provided with a cover 73 which is hinged by 55 its rear end to the side walls to drop downwardly and forwardly to have an apron extend along the side of the walls 12 and 13 and also across the front side therebetween. 60 The top side of the cover 73 is made to be flush with the plate 67 so as to leave no offset or projection at the juncture therebetween. A drawer 74 is slidably entered with- 65 in the front end of the housing 10 between false walls 75 and 76 so as to retain the drawer

centrally in line with the drawer 34 carried in the carriage 18. The forward end of the drawer extends upwardly to engage under the apron carried by the cover 73 and a lock 77 is provided to maintain the cover 73 in a 70 closed position thereby preventing the withdrawal of the drawer 74. The partition 36 is provided with slots at each end through which the slides 16 and 17 may pass freely 75 when the carriage 18 is shifted to its forward position, the slides being sufficiently long so as to have sufficient bearing length within the guides to prevent the downward tilting of the carriage 18 when it is shifted to its rear position and its major portion extends outwardly beyond the housing 10. 80

A short table 78 extends horizontally forward from the top of the partition 36 for a short distance and has a downturned lip 79 across its forward edge. This table 78 is at 85 the same elevation or slightly above that of the plate 51 which extends rearwardly from the other side of the partition. A tongue 80 is fixed to the under side of the cover 73 above the forward part of the table 78 and is curved 90 around downwardly and forwardly to extend well below as well as forwardly of the lip 79.

The structure above described is intended to use forms superposed one over the other, 95 perforated between the ends of the forms and folded in a zig-zig manner to form a flat pack. Also each set of forms is provided with transversely spaced apart punch holes as are customarily employed for filing purposes. Referring to the drawings, a pack 81 having the above defined characteristics, is placed in the drawer 34 within the carriage 18 and the superposed plies of forms are brought around from the pack over the rear edge of the platform 21, this edge being preferably rolled to aid the paper in slipping therearound. The superposed forms, here shown as three in number, are brought forwardly over the platform 21 across the 100 springs 52 and 53 to be engaged over the pins 56 and 57 through the punch holes provided in the forms. In thus placing the forms over the platform 21, the housing cover 70 is 105 rocked around forwardly to be out of the way and the carriage cover 27 is rocked around 110 laterally so that the paper may be carried directly across the platform without difficulty. The paper is slipped under the in-turned fingers 28 and 29 at the rear of the platform so as to retain the forms closely 115 against the platform 21 until the cover 27 is dropped down thereover. Where the forms themselves do not carry a carbon back coating so as to cause an impression to be made on underlying plies, carbon sheets 83, here 120 shown as two in number, are carried on the spool 26 and are threaded between the first and second plies of forms as indicated in Fig. 8 to have the carbon sheets carried on across 125 to extend somewhat beyond the other side of 130

the platform 21 so that when the cover 27 is dropped into its closed position, pins 84 may engage the projecting ends of the carbon sheets to prevent the sheets from slipping 5 back from between the forms.

By reason of the inherent nature of the zig-zag form of pack, the individual forms are held in alignment by reason of the folds of the different plies nesting one within the 10 other so that the forms as brought around onto the top side of the platform 21 are in register. The under or lower ply of the forms has its forward end inserted to under the tongue 69 while the upper two plies are 15 placed on top of the apron 68. While reference is made to the pack as being formed to have three plies, it is obvious that less or more plies may be used as desired depending upon the number of copies desired. The 20 pack with the three plies is here shown as but one example of forms which may be used. In the view as shown in Fig. 1, the forms are shown as having been placed ready for the machine to be operated. In order to place 25 the carriage 18 in the proper position to permit writing on the form, the handle 31 is grasped and pulled rearwardly with the safety pins 63 sliding back over the forms. The handle 31 is carried rearwardly until the carriage 30 strikes the stop 49 at which position the handle 31 is at the rear end of the window in the cover 70 at which position, the pins 63 drop into the holes 85 of the next adjacent set of forms as shown in Fig. 4 where it is to be 35 seen that the diameter of the pin 63 is much less than that of the holes 85 so that the pins are in reality out of contact with the periphery of the holes in the forms. The forms over the platform 21 are spring pressed against 40 the cover 27 by the springs 52 and 53 so that as the carriage 18 is carried forwardly by pushing on the handle 31 the forms are carried along with the carriage to cause the forms to be disengaged from the pins 56 and 45 57 by reason of the forward set of forms being pushed forwardly and having the front ends thereof lifted by reason of the guides 58 and 59 extending up over the pins. The upper two forms will thus be carried on out 50 up over the apron 68 while the under form is carried under the apron forwardly over the table 78 to strike the tongue 80 to be deflected downwardly toward the front end of the drawer 74. The carriage 18 is moved forwardly until the handle 31 is at the extreme 55 forward end of the window in the cover 70 at which point the carriage is held by reason of the latch 37 as above described. In this position the form 86 has been advanced forwardly to have the holes 85 brought up over the pins 56 and 57 and the other set of forms have been carried completely ahead of the front end of the cover 70 so that the upper 60 two forms may then be torn off with the forward edge of the cover serving as a knife to 65

facilitate the tearing of the forms across the perforated lines. In order to have the pins 56 and 57 extend through the holes 85 in the forms thus brought up thereto, the fingers 65 and 66 are provided to direct the forms and 70 press them downwardly about the pins as the holes 85 are brought to register thereover so that the top side of the top form 86 is then held down so that the forms become engaged under the forward hooked ends of the guides 75 58 and 59 so that backward movement of the forms is prevented. When the pins 63 strike the guides 58 and 59 as the form 86 is advanced, the pins are lifted by riding up over these guides so as to clear the edges of the 80 holes 85. After the form has been filled in as desired, it and its under copies may then be removed by the operator upon grasping the handle 31 by the right hand and pressing the lever 39 forwardly by the thumb to release the carriage from the latch 37. The carriage is then pulled rearwardly in order to position another set of forms over the platform 21 from the pack 81, the pins 56 and 57 holding the forms against rear travel so 85 that the springs 52 and 53 may slide back under the forms to get a new grip on the next set of forms thus brought around on the top of the platform 21. As soon as the handle 31 has reached its rear limit of travel it is 90 then shifted forwardly again to the forward limit of travel advancing the forms then written upon forwardly of the cover 70. The pins 63 upon the rear movement of the carriage slide back on top of the forms since 95 they had been lifted out of the holes 85 by reason of the elevation of the guides 58 and 59. The pins 63 do not function to aid in any way the feeding of the forms forwardly. They are provided merely as a safety device 100 for such an emergency as when the forms coming from out under the cover 70 become caught or held in some manner which would overcome the frictional resistance of the forms between the springs 52 and 53 and the 105 under side of the cover 27. In such an event, the pins 63 being in the holes 85 will advance to the forward sides thereof and positively hold the forms from slipping back any further over the platform 21 and thus maintain 110 the forms in their own relative positions on the platform as well as in register one with the other. As above indicated the springs 52 and 53 frictionally hold the superposed strips of forms in place over the platform 21. In addition to the friction grip by these 115 springs, there is the friction set up by the carbon sheets interleaved between the strips which in itself would ordinarily be sufficient to retain the forms without slipping over the platform 21. The carbon sheets are slipped back between the strips from the set of forms engaged over the pins 56 and 57 to the next set of forms when the carriage 18 is pulled 120 back rearwardly. In this way the frictional 125 130

resistance between the carbon sheets and the strips is overcome while the strips remain engaged over the pins so that the changing of the carbon sheets does not pull the forms out of register. A stop 90 is provided to extend upwardly from the floor 11 to positively limit the forward travel of the carriage, the stop being located in any suitable position to be in the path of the carriage 18 or some member 10 connected therewith, here shown as being in the path of the arm 50 which is employed to strike the back stop 49.

It is the usual custom where three superposed strips of forms are used to keep one strip of forms for a record of the day's transactions. This record strip is the one which is on the under side of the three strips and is next to the platform 21 and is also the one which feeds forwardly under the tongue 69 20 to pass over the table 78 and around under the tongue 80 to within the drawer 74 where it is maintained in a concealed manner proof against alterations. The relation between the table 78 and tongue 80 is such that when the 25 perforated line across the end of one form reaches the outer vertical end of the drawer 74 as indicated in Fig. 2, that form 87 will then drop around rearwardly under the influence of gravity about that perforated line 30 as a hinge joint when the next attached form is advanced over the table 78 to have the upper end of that form 87 along its perforated line to drop downwardly as indicated by the dash lines to have its fold line 88 drop to allow the form 87 then to spring downwardly 35 and backwardly as in the shape indicated by the dash line 89 so that the forms thus advanced to within the drawer 74 will assume their original zig-zag shape to build up a pad 40 in single strip form. The shape of the lip 79 along the table 78 and the curvature of the tongue 80 are properly formed to aid and direct the forms to allow them to fold back and forth within the drawer 74. Also to aid this 45 folding, a false floor 91 is placed in the forward end of the drawer 74 to form an inclination so that the rear folds will be lower than the forward folds in order to insure the proper folding of the forms.

50 While I have here shown and described my invention in the one particular form as now best known to me, it is obvious that structural changes may be made without departing from the spirit of the invention and I therefore do 55 not desire to be limited to that precise form beyond the limitations as may be imposed by the following claims.

I claim:

60 1. In an autographic manifolding machine, a supporting housing, a carriage movable lengthwise of the housing and having means to support a plurality of superposed strips of paper provided with forms arranged in sets, a platform on the carriage forming a writing table and so arranged that said strips

may be led over the rear end thereof to receive one set of forms on the platform to have their forward ends at the front of the platform, fixed pins carried by the housing forwardly of the carriage adapted to engage said 70 forward form ends and hold them against rearward movement when the carriage is moved rearwardly, and means lifting said ends from said pins permitting said set of forms to be shifted forwardly beyond said 75 pins upon forward movement of the carriage.

2. In an autographic manifolding machine, a supporting housing, a carriage movable lengthwise of the housing and having means to support a plurality of superposed strips 80 of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said 85 forward form ends and hold them against rearward movement when the carriage is moved rearwardly, and means lifting said ends from said pins permitting said set of forms to be shifted forwardly beyond said 90 pins upon forward movement of the carriage, and means carried by the carriage gripping 95 said set of forms on said platform to retain them against longitudinal displacement.

3. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end 100 thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said 105 pins upon forward movement of the carriage, and means carried by the carriage gripping 110 said set of forms on said platform to retain them against longitudinal displacement.

4. In an autographic manifolding machine, a form engaging means comprising a fixed vertical pin, and a guide sloping up from the back of the pin to at least the same 115 elevation as the top of the pin.

5. In an autographic manifolding machine, a form engaging means comprising a fixed vertical pin, and a guide sloping up from the back of the pin to at least the same 120 125 130 elevation as the top of the pin.

elevation as the top of the pin, and a projection extending forwardly from the pin forming a hook therewith.

6. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, and forwardly directed fingers carried by the carriage over said forms arranged to pass along a side of said pins and press said forms down over said pins.

7. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from pins permitting said set of forms to be shifted forwardly beyond said pins upon forward movement of the carriage, a latch engaging said carriage at its forward end of travel, and a lever extending from the housing shifting said catch from engagement upon forward rocking.

8. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage,

means preventing reverse travel of said carriage between its front and rear end of travel during movement in one direction, and shifting means operating said reverse preventing means to permit return movement of the carriage.

9. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, means preventing reverse travel of said carriage between its front and rear end of travel during movement in one direction, and shifting means operating said reverse preventing means to permit return movement of the carriage, said reverse means comprising a rack fixed to the housing, a pair of oppositely turned dogs pivoted to the carriage and normally dropping against said rack, a shiftable bar having a pin extending to between the dogs, and said shifting means comprising a stop at each end of travel of the carriage in the path of said bar whereby one dog is dropped and the other dog is raised at each end of travel.

10. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of said forms thereover to have their forward ends at the front of the platform, fixed pins carried by the housing forwardly of the carriage adapted to have said form forward ends impaled thereon and hold the forms against rearward movement when the carriage is moved rearwardly, and forwardly extending fingers carried by the carriage located to pass along a side of said pins upon forward travel of the carriage to press said forms down over the pins.

11. In an autographic manifolding machine, a supporting housing, a carriage movable lengthwise of the housing and having means to support a plurality of superposed strips of paper provided with forms arranged in sets, a platform on the carriage forming a writing table and so arranged that said

- strips may be led over the rear end thereof to receive one set of said forms thereover to have their forward ends at the front of the platform, fixed pins carried by the housing forwardly of the carriage adapted to have said form forward ends impaled thereon and hold the forms against rearward movement when the carriage is moved rearwardly, and forwardly extending fingers carried by the carriage located to pass along a side of said pins upon forward travel of the carriage to press said forms down over the pins, and guides sloping from the rear up over said pins to lift said forms by their sliding thereover upon forward return travel following a back movement of the carriage.
12. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of said forms thereover to have their forward ends at the front of the platform, fixed pins carried by the housing forwardly of the carriage adapted to have said form forward ends impaled thereon and hold the forms against rearward movement when the carriage is moved rearwardly, and forwardly extending fingers carried by the carriage located to pass along a side of said pins upon forward travel of the carriage to press said forms down over the pins, and guides sloping from the rear up over said pins to lift said forms by their sliding thereover upon forward return travel following a back movement of the carriage, an apron carried by the housing forwardly of and sloping downwardly and rearwardly toward said pins, and a tongue extending from the apron to between and somewhat below the tops of the pins, said apron deflecting the upper of said strips upwardly, and said tongue deflecting the lower strip to under the apron.
13. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, an apron carried by the housing forwardly of and sloping downwardly and rearwardly toward said pins, and a tongue extending from the apron to be between and somewhat below the top of the
- strips, said apron deflecting the upper of said strips upwardly, and said tongue deflecting the lower strips to under the apron.
14. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of said forms thereover to have their forward ends at the front of the platform, fixed pins carried by the housing forwardly of the carriage adapted to have said form forward ends impaled thereon and hold the forms against rearward movement when the carriage is moved rearwardly, and forwardly extending fingers carried by the carriage located to pass along a side of said pins upon forward travel of the carriage to press said forms down over the pins, and guides sloping from the rear up over said pins to lift said forms by their sliding thereover upon forward return travel following a back movement of the carriage, an apron carried by the housing forwardly of and sloping downwardly and rearwardly toward said pins, and a tongue extending from the apron to between and somewhat below the tops of the pins, said apron deflecting the upper of said strips upwardly, and said tongue deflecting the lower strip to under the apron.
15. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, a form receiving compartment in the front end of the housing, and form folding means comprising a short platform over which one of said strips is directed, and a forwardly and downwardly turned tongue spaced forwardly of the platform.
16. In an autographic manifolding machine, a supporting housing, a carriage movable lengthwise of the housing and having means to support a plurality of superposed strips of paper provided with forms arranged in sets, a platform on the carriage forming a writing table and so arranged that

said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, a form receiving compartment in the front end of the housing, and form folding means comprising a short platform over which one of said strips is directed, and a forwardly and downwardly turned tongue spaced forwardly of the platform, said compartment having a length substantially that of each set of forms, and having a floor sloping upwardly and forwardly.

17. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, and safety pins carried by the carriage normally dropping against said forms adapted to engage therewith upon relative backward movement of the forms on said platform.

18. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, and safety pins carried by the carriage normally dropping against said forms adapted to engage therewith upon relative backward movement of the forms on said platform, said pins being spaced apart to be in

the paths of said fixed pins to be lifted from engagement from the forms by said fixed pins in passing thereover.

19. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, and safety pins carried by the carriage normally dropping against said forms adapted to engage therewith upon relative backward movement of the forms on said platform, said pins being spaced apart to be in the paths of said fixed pins to be lifted from engagement from the forms by said fixed pins in passing thereover, and guides back of said fixed pins over which said safety pins may ride to be raised above the fixed pins.

20. In an autographic manifolding machine, a supporting housing, a carriage movable lengthwise of the housing and having means to support a plurality of superposed strips of paper provided with forms arranged in sets, a platform on the carriage forming a writing table and so arranged that said strips may be led over the rear end thereof to receive one set of forms on the platform to have their forward ends at the front of the platform, fixed pins carried by the housing forwardly of the carriage adapted to engage said forward form ends and hold them against rearward movement when the carriage is moved rearwardly, and means lifting said ends from said pins permitting said set of forms to be shifted forwardly beyond said pins upon forward movement of the carriage, and safety pins carried by the carriage normally dropping against said forms adapted to engage therewith upon relative backward movement of the forms on said platform, said pins being spaced apart to be in the paths of said fixed pins to be lifted from engagement from the forms by said fixed pins in passing thereover, and guides back of said fixed pins over which said safety pins may ride to be raised above the fixed pins, said safety pins having longitudinal slots across their under sides to slidably engage over said guides whereby said forms are depressed to be below the tops of said guides.

In testimony whereof I affix my signature.

LUTHER R. HANNA.
